UNITED STATES PATENT OFFICE

ERICH BANDOLY, OF CHICAGO, ILLINOIS, ASSIGNOR TO CENTRAL SCIENTIFIC COMPANY,
OF CHICAGO, ILLINOIS, A CORPORATION OF ILLINOIS

PROCESS OF MAKING OIL TRAPS FOR VACUUM PUMPS AND SIMILAR ARTICLES

Original application filed April 9, 1926, Serial No. 100,901. Divided and this application filed January 17, 1929. Serial No. 333,249.

This invention relates to the manufacture of oil traps for vacuum pumps and similar articles, and has for its principal object to provide a simple and economical process of 5 making them impervious to fluids.

Further objects and advantages of the invention will become apparent as the description is read in connection with the accompanying drawings, in which—

10 Fig. 1 is a sectional view through an eccentric pump and oil bath taken along the axis of the driving shaft;

Fig. 2 is a similar section taken on the line 2—2 of Fig. 1;

15 Fig. 3 is a section of the oil trap taken on the line 3—3 of Fig. 1;

Fig. 4 is an elevation of the inside face of the removable wall of the oil bath casing, and

20 Fig. 5 is a view similar to Fig. 1, illustrating a modified construction of oil trap and oil bath.

But these specific illustrations and corresponding specific descriptions are used to make the invention clear and are not intended to require a limitation of the claims 25 other than is made necessary by the prior art.

The apparatus illustrated includes an oil bath generally indicated by A and an eccentric pump generally indicated by B and mounted in the bath.

The pump is of the eccentric type including two units, each composed of a cylinder 10, an eccentric rotor 11, driven by a shaft 12 mounted concentric with the cylinder and a blade 13 (Fig. 2) reciprocating in a slot 14 in the cylinder wall and contacting with the outer surface of the rotor 11.

In order to facilitate the assembly of the 40 pump with the bath and the support of the pump therein, one wall 31 (Fig. 1) of the bath casing is made readily removable and equipped with fastenings for securing the pump to it. The remainder of the bath 45 casing is made in one piece comprising a bottom 32 and sides 33, 34 and 35, each side having an inturned flange 36 which, together are adapted to receive a removable cover 37.

The upper portion of the removable wall 50 is formed hollow to provide a trap cham-

ber 38 which is connected with the inlet passage 28 at the bottom and equipped with a hose nipple 39 by which the pump may be connected with the vessel to be exhausted.

In the form shown in Fig. 1 the bath is 55 made of aluminum die casting and the chamber 38 is provided with a lining shell of steel composed of a cup-shaped element 40, a disk 41 closing its open side, and a reenforcing strut 42 bent back and forth as indicated in Fig. 3, and lying between the opposite sides of the chamber. A short piece of steel tubing 43 extends from the inner side of the chamber to the outer face of the plate 15. A sealing cup 44 has a shouldered neck 45 extending through the lining and the aluminum and threaded to receive the hose nipple 39.

In practice, the reinforcement is welded 70 at a few points to the disk 41 and the disk 41 is welded to the rim of the cup 40, the tubing 43 and the sealing cup 44 are welded to the disk and the cup in the position shown. This assembly forms an insert which is 75 placed in the molding die and about which the jacket of aluminum, zinc, alloy, or other light metal is cast.

The steel liner makes the trap mercury 80 proof and in the majority of cases will make it also air tight. However, to insure uniformly air tight structures in production the pores should be sealed with a substance having a vapor pressure below any pressure which the pump will be called upon to produce. Certain japs have a vapor pressure 85 of 1/100 of a micron at 110° C. and these are suitable for impregnating the trap.

The sealing process is accomplished in the following manner:—Plug the tubing; screw 90 the cups 44 onto the nipples of a manifold connected with a vacuum pump; exhaust the trap chambers and submerge the castings in liquid japan; continue the submerging until the atmospheric pressure has had an ample opportunity to force the japan into the minute pores; remove and bake to solidify the japan; immerse again without exhausting and bake the second time.

The lower portion of the removable wall 31 is thin and solid as indicated at 46, and

equipped with a marginal flange 47 terminating in alignment with the inner face of the upper portion; this face 48 and the corresponding face of the flange 47 are ground to 5 cooperate with the ground face 49 of the plate 15 to form a proper joint.

The plate 15 is extended beyond the margins of the cylinder 10, as indicated at 50, (Fig. 2) and drilled and tapped to receive 10 studs 51 by which the pump is secured to the wall 31, the latter being thickened at 52 and drilled and tapped to receive the studs.

The removable wall is also thickened and drilled at 54 to receive studs which thread 15 into tapped openings in the body of the bath and secure the removable wall in place.

The lower portion 46 of the wall 31 is provided with a boss 55 aligned with a brass insert 56, which, together with the gland 57 20 and packing 58, forms a stuffing box for the shaft 12.

When the bath is made of cast iron the removable wall 60 (Fig. 5) is formed with a trap chamber 61 without any lining, corresponding to that shown in Figs. 1 and 3. Any pores in the walls of this chamber may 25 be sealed by the procedure described above.

This application is a division of my application Serial No. 100,901 filed April 9, 30 1926.

I claim as my invention:

1. The process of closing the pores of hollow metallic traps for vacuum pumps which includes creating a pressure differential between the exterior and interior surfaces of the article, applying a temporarily liquid filler to the surface subjected to the higher pressure, and maintaining the pressure differential a sufficient length of time to permit 40 the filler to occupy the pores.

2. The process of closing the pores of hollow metallic oil traps for vacuum pumps which includes reducing the pressure on the interior of the trap, applying a temporarily 45 liquid filler to the exterior of the trap and maintaining the reduction in pressure on the interior a sufficient length of time to permit the filler to occupy the pores.

3. The process of closing the pores of hollow metal articles designed to enclose a vacuous space, which includes creating a pressure differential between the exterior and interior surfaces of the articles, applying a temporarily liquid filler to the surface subjected to the higher pressure and maintaining the pressure differential a sufficient length of time to permit the filler to occupy 55 the pores.

4. In the treatment of metallic parts to be subjected to vacuum, that method of rendering the parts impervious to diffusions of gases therethrough which consists in subjecting one side of the metallic part to a vacuum of substantial degree, covering the 60 part, with the vacuum still applied, with a

substance temporarily liquid, the vapor pressure of which in a solid state is below the order of vacuum to which the said metallic part will be subjected, and continuing such treatment until the voids in the metal are 70 filled.

5. That method of rendering oil traps for vacuum pumps impervious to the diffusion of gases through the material of said trap, which consists in subjecting one side of the trap to a vacuum of substantial degree, covering the part, with the vacuum still applied, with a substance temporarily liquid, the vapor pressure of which does not exceed the vapor pressure of the sealing fluid to be used in said trap, continuing such process until the voids in the substance of the trap are filled, and subsequently treating said trap to change the filler material to a solid substance. 80

6. That method of rendering oil traps for vacuum pumps impervious to the diffusion of gases through the material of said trap which consists in subjecting one side of the trap to a vacuum of substantial degree covering the part, with the vacuum still applied, with a substance temporarily liquid, the vapor of which in a solid state does not exceed the lowest pressures which can be produced by the pump, continuing such process until the voids in the substance of the trap are filled, subsequently treating the trap to change the filling material into a solid substance, and then coating the trap with the same filling material and treating to change the coating into a solid substance. 90

In testimony whereof I affix my signature. 100
